UNITED STATES PATENT OFFICE.

BENJAMIN WEXLER, OF BROOKLYN, NEW YORK, ASSIGNOR TO THE PEELLE COMPANY,
A CORPORATION OF NEW YORK.

ELEVATOR-DOOR.

1,295,655.

Specification of Letters Patent. Patented Feb. 25, 1919.

Application filed December 3, 1917. Serial No. 205,034.

To all whom it may concern:

Be it known that I, BENJAMIN WEXLER, a citizen of the United States, residing at the borough of Brooklyn, city of New York, county of Kings, and State of New York, have invented certain new and useful Improvements in Elevator-Doors, of which the following is a specification, reference being had therein to the accompanying drawings, 10 which form a part thereof.

My invention relates to elevator doors and more particularly to a type of automatic or self-closing fireproof door and in the mechanisms for stopping and holding said door 15 in the opened position. The invention of this application is an improvement in the type of door patented to me March 10th, 1914, by Letters Patent No. 1,089,451.

Elevator doors of the type to which my 20 invention relates, are ordinarily used for closing the door openings in a shaft for freight elevators, and are therefore of fairly large dimension and possess considerable weight. It is a common practice to manufacture these doors at the factory, and to 25 adjust them with relation to the door opening, when installing them in the elevator shaft. It has been found in practice, however, that considerable difficulty is experienced in adjusting the stop and the latch 30 mechanism, so as to bring the top frame, or truck bar, of the lower door section, on substantially the level of the door sill while preserving a relation of parts which will insure the proper locking of this section when 35 in the opened position. In the form of the invention shown in my aforesaid Letters Patent, the practice was to secure the frame carrying the stop and the latch member, to 40 the guide rail after the latter was secured to the wall within the elevator shaft, it being impossible to vary the relation of this frame to the door sill after it once had been installed. Furthermore, the time and labor 45 required to install these mechanisms, added materially to the cost of the installation, and required considerable skill in order to secure the proper relation of parts.

By means of my present invention, I am 50 enabled to provide an elevator door, the stop and latch mechanisms of which may be accurately assembled in the apparatus in the proper permanent relation in the factory at comparatively small expense, while being 55 capable of quick and sufficiently accurate

adjustment when mounting the door in the elevator shaft, so as to permit the door to be so set as to bring the top of the lower door section thereof on substantially the level of the sill of the door opening without varying 60 the relative operative positions of the stop and the latch mechanism. The construction of these mechanisms is such that irrespective of the degree of adjustment thereof, that relation of the stop and the latch members 65 determined during the manufacture of the door structure while in the factory, remains constant irrespective of the degree of adjustment thereof necessary to insure the positioning and locking of the lower door section 70 in the proper relation to the sill. The stop and latch mechanism instead of being permanently applied to the rail after it is secured to the wall of the elevator shaft, are mounted upon the vertical rail carrying the 75 guides for the shoes of the door sections, by means of a member permanently secured to this rail while in the factory, said mechanisms being readily separable from the rail at all times, thus not only facilitating the 80 simultaneous adjustment of these mechanisms with relation to the rail and the sill of the door opening, but the installation of the door in the shaft. Furthermore, the initial cost of production and the cost of in- 85 stallation, are materially reduced.

The stop and latch mechanisms are so constructed as to be capable of use with top bars of different standard dimensions without material alteration and permit the production thereof with a minimum of machine finishing thereon.

The invention consists primarily in an elevator door embodying therein the combination with an overbalanced, downwardly movable, sliding door section having a laterally projecting hanger bar thereon, and guide rails secured adjacent the door opening co-operating with said door, of a combined stop and latch mechanism comprising a lock 95 plate permanently secured to a guide rail, a fitting having a stop shoulder thereon adapted to be operatively engaged by the bottom of the end of said hanger bar, a latch member carried by said fitting adapted to 100 engage the top of said hanger bar when the door is opened, said fitting and said lock plate being provided with co-operating means whereby said stop member and said latch member may be simultaneously adjusted 110.

without disturbing the relative positions thereof with relation to said hanger bar, and means securing said fitting and said lock plate in any adjusted position, and means carried by an elevator car coöperating with said latch member whereby the release of the latch member is prevented while a car is at the door opening; and in such other novel features of construction and combination of parts, as are hereinafter set forth and described and more particularly pointed out in the claims hereto appended.

Referring to the drawings:

Figure 1 is a front elevation of a portion 15 of an elevator door embodying my invention, a portion of the hanger bar being broken away to more clearly disclose the structure of the latch member;

Fig. 2 is a side view thereof showing the 20 shoe carried by the car in operative relation to said latch mechanism;

Fig. 3 is a plan view of the lock plate and the fitting coöperating therewith, showing a portion of the door structure and the elevator shaft;

Fig. 4 is a side elevation from the right of Fig. 3;

Fig. 5 is a view, similar to Fig. 4, showing another embodiment of the invention; and

Fig. 6 is a plan view of the form of the invention shown in Fig. 5.

Like letters refer to like parts throughout the several views.

In the embodiment of my invention shown 35 in the drawings, I have illustrated it in connection with a type of door employing two oppositely movable, vertically sliding door sections *a* and *b*, the upper section *a* being of relatively greater weight than the lower section *b* so as to impart to the door a normal tendency to close when opened. Said sections are connected by the usual chain and bar suspension members *c* passing over the pulleys *c'* adjacent the lintel of the door opening.

Within the elevator shaft, the wall of which is indicated at *d*, and at opposite sides of the door opening indicated at *d'*, are the usual vertically extending angular rails *e*, having secured thereto guide rails *e'* coöperating

50 with the shoes *a'* and *b'* upon the door sections *a* and *b* respectively. The suspension members *c* are connected with lugs *a²* adjacent the bottom of the door section *a* and with an angular hanger bar *f* carried by the top 55 of the section *b* and having laterally projecting ends *f'* projecting beyond the rails *e*. The lower door section *b* is also provided with a top bar *b²* superimposed upon the said hanger bar, said bar *b²* being of sufficient 60 width to substantially span the gap between the sill *d²* of the door opening and the platform of an elevator car, to form what is known as a "truckable" door structure.

This construction is old and well known to 65 the art and merely typifies the general char-

acter of doors in combination with which my invention is adapted to be utilized.

In smaller sizes of elevator doors, it has been a practice to use a stop only on one of the rails *e* and a combined stop and latch mechanism upon the other rail, while in larger sizes of doors, a combined stop and latch mechanism is used upon both rails. In the accompanying drawings, I have shown the invention applied to a smaller type of door, although, it is apparent that to apply the combined stop and latch mechanism to both rails would involve merely duplication of this mechanism in the door structure.

In the embodiment of the invention shown 80 in the drawings, the combined lock and latch mechanism comprises a lock plate *g* permanently attached to one of the rails *e* at the factory, in a position which, when the rail is installed in the elevator shaft, will bring said plate below the sill of the door opening. This plate *g* is provided with horizontally extending projections or teeth *g'* projecting beyond the edge of the rail *e*.

Coöperating with the plate *g*, is a fitting 90 comprising a base *h* having a side flange *h'* adapted to bear upon one face of the lock plate *g*, an overhung portion *h²* adapted to project across the edge of said plate *g* and a plate *h³* extending parallel with the flange *h'* 95 and having thereon teeth *h⁴* adapted to coöperate with the teeth *g'* upon the lock plate *g*. The top of the plate *h³* is recessed at the edge thereof toward the wall of the elevator shaft, to form a stop *i* adapted to receive the projecting end *f'* of the hanger bar *f* of the lower door section *b*.

Pivottally mounted upon the said fitting, is an oscillatory latch lever *j*, one end of which has slidably mounted therein a bolt *j'* normally thrust by a spring *j²* carried by the said lever *j*, into the path of movement of the end *f'* of the said hanger bar *f*. The lower end of the lever *j* is provided with an impact member *j³* adapted to be engaged by a shoe *k* carried by an elevator car for the purpose of making the latch mechanism operative when a car is substantially level with the sill of the opening closed by the door, and inoperative at all other times.

In the construction shown in the accompanying drawings, the lever *j* is so overbalanced as to impart to it a normal tendency toward a movement which will bring the bolt *j'* out of the path of movement of the end of the hanger bar, although, means other than gravity may be relied upon, if desired, for securing this action of the latch lever. The lever *j* is also provided with a stop *j⁴* adapted to engage the base *h* of the fitting, to insure accuracy in the positioning of the latch bolt *j'* when a car is in position to be in operative relation to the impact member *j³*.

To facilitate the adjustment of the latch mechanism when installing the door struc- 130

ture, I preferably make the impact member j^3 adjustable in relation to the lever j , by a slot and bolt connection j^5 between the said impact member and said lever.

5 The lock plate g has a vertically extending countersunk slot therethrough indicated at g^2 in Fig. 1 of the drawings, and adapted to register therewith is a slot h^5 through the flange h' of the adjustable fitting, through 10 which slots and bolts opening in the plate h^3 , bolts l may pass to secure said fitting and said lock plate in any adjusted position. In the accompanying drawings, I have shown three such bolt openings while only two bolts are 15 employed, the additional bolt opening being provided to permit the shifting of one of the bolts in order to increase the range of adjustment of the fitting.

The teeth h^4 and g' constitute coöperating 20 interlocking members, by means of which the stop i and the latch lever may be simultaneously adjusted toward or away from the sill of the door opening, without varying the distance between said stop i and the bolt j' , 25 which distance is predetermined when assembling the combined stop and latch mechanism in the factory, and remains constant so as to properly position said stop and said bolt at all times so that the former will, when the 30 door is opened, engage the lower edge of the projecting end of the hanger bar and the latter will engage the upper edge thereof.

The base h of the adjustable fitting is provided with studs $m-m'$ in which is slidably 35 mounted a spring sustained plunger n positioned in the plane of movement of the hanger bar f so as to be engaged thereby when the door is approaching the limit of its downward movement. The plunger n is 40 provided with a spring seat n' , between which and the stud m' , is seated a spring n^2 having the two-fold function of a cushioning spring for the door section as it is opened, and a starting spring for insuring 45 the release of the latch member and an initial upward impulse of the door after a car leaves the floor level and the shoe k has passed from its operative relation to the impact member j^3 .

50 The latch lever j is provided with a large hub portion indicated at o , adapted to fit between the flange h' and either of two studs $p-p'$ carried by the base h of the adjustable fitting, said lever being mounted 55 in relation to said fitting by means of the bearing pin q . I provide two studs $p-p'$ in order to standardize the fitting and permit its use with doors having hanger bars of 60 different depths. Ordinarily, these hanger bars are either three or four inches deep, according to the size of the door, so that by spacing the centers of the openings through said studs, one inch apart, the same fittings 65 may be used with either a three or a four inch hanger bar. When using a three inch

hanger bar, the pin q will be passed through a lug p' while with a four inch hanger bar, the pin will be passed through the lug p . When the lug p' is used, the lug p is broken away from the base so as to leave 70 clearance for the spring j^2 .

The base h , flange h' , overhang h^2 and plate h^3 of the adjustable fitting, must be so constructed and associated as to prevent movement of any of these parts in relation 75 to the other, it being necessary, in order to preserve the distance between the stop i and the bolt j' to have the fitting and its appurtenances move as a unit.

In the form of the invention shown in 80 Figs. 1 to 4, these parts are shown as being formed of one integral casting but when manufacturing these parts in large quantities, foundry difficulties and warping during annealing may make it desirable, as a matter of economy, to make the plate h^3 separate from the other portions of the device and provide coöperating connecting means whereby in adjusting the fitting, said plates must have movement in unison. In the 85 90 form of the invention shown in Figs. 5 and 6, the structure is identical to that heretofore described, with the exception that the plate h^3 is cast in a separate piece from, and united with, the overhang h^2 by means of 95 tongues r carried by said overhang and coöperating sockets r' in the plate h^3 . This form of the invention also differs from that shown in Figs. 1 to 4, in that the slot h^4 instead of being of sufficient width to permit the bolts l to pass completely therethrough and engage the countersunk slot g^2 in the plate g , is sufficiently narrow to cause the head of the bolt to engage the flange h' , thus insuring the proper binding of said 100 flange upon the plate g , and preserving the proper relation between said flange and the plate h^3 . The various lugs $m-m'$ and $p-p'$ are preferably cast integrally with the base h .

110 When only one combined stop and latch mechanism is used in a door structure, the other rail e has permanently secured thereto a plate s similar to the plate g and an adjustable stop s' thereon secured in relation thereto by means of the bolts s^2 . This construction forms no part of my present invention, and is merely used in order to afford a rigid support for the hanger bar f upon opposite sides of the door opening d .

115 The operation of the herein described structure is substantially as follows:—

When manufacturing the door structure, the plate g is riveted, welded, or otherwise 120 permanently secured to its rail e in a position which will bring it below the sill d^2 of the door opening adjacent which the rail is to be mounted.

125 The fitting coöperating with said plate g and its appurtenances are then assembled, 130

with the distance between the stop i and the bolt j' approximating the depth of the hanger bar of the door section to be used. When these parts are assembled in the factory, it is possible to secure a fixed definite relation between the stop i and the bolt j' which is very difficult to secure, if the stop and the latch members are capable of relative movement toward or from each other.

- 10 In installing the door structure, the doors are hung in the usual manner, and the fitting is passed over the plate g with the teeth h^4 and g' so enmeshed as to cause the projecting ends f' in the hanger bar f to engage the stop i when the truck bar of the door section is on substantially the level of the sill d^2 . It is merely necessary to secure the proper adjustment of the fitting to bring the stop to this point, since irrespective of the adjustment of the fitting, the relation of the stop i and the bolt j' will always be such as to properly engage opposite edges of said hanger bar. When the stop has been properly located, it is merely necessary to insert and tighten the bolts l thus preventing any likelihood of a loss of the adjustment. These bolts themselves are relieved of practically all strain by the tooth formation above referred to.
- 25 The manner of installing the form of the invention of Figs. 5 and 6 is substantially like that heretofore described, except that by reason of the plate h^3 being separable from the overhang h^2 , said plate may be moved away from the plate g sufficiently to permit the teeth h^4 to clear the teeth g' and thus facilitate adjustment of the fitting.

When the combined stop and latch mechanism is permanently secured to the rail e , the normal position of the bolt j' will be at one side of the plane of movement of the hanger bar f . When a car comes to rest at a door opening d' , however, the shoe k will engage the impact member j^2 thus rocking the lever j , until the stop j^4 of the lever j engages the base plate h . When the lever is in this position, the bolt j' will be projected across the plane of movement of the hanger bar, so that when the door is opened, and said hanger bar engages said bolt, it will recede within the opening in the lever in which it is mounted, against the tension of the spring j^2 thus permitting the passage of the hanger bar. Immediately thereafter the projecting end f' of the hanger bar will engage the plunger n , forcing it downwardly against the tension of the spring n^2 thus cushioning the door in the final stage of its descent until it engages the stop i . As the hanger bar engages the stop i , the spring j^2 will force the bolt j' across the upper edge of the hanger bar, thus locking the door in its opened position.

So long as the car remains at the door opening, the bolt j' will remain operative to

prevent the closing of the door. As soon, however, as the car leaves this floor, the shoe k passes out of its operative relation to the impact member j^2 permitting the latch lever j to oscillate slightly, this movement being assisted by the upward thrust of the plunger n from its spring n^2 which imparts a starting impulse to the door and insures the proper actuation of the latch lever. The section a being heavier than the section b insures the complete closing of the door.

The advantages of other structural characteristics in the combined stop and latch mechanism have been heretofore described and further consideration thereof is believed unnecessary.

The essential characteristic of the invention is the structure of the combined stop and latch mechanism by which the mechanism may be readily adjusted vertically of the rail e and set in any adjusted position without varying the fixed predetermined relation of the stop i and the bolt j' .

It is not my intention to limit the invention to the details of construction shown in the accompanying drawings, such details being merely those incidental to the adaptation of the invention to one type of door, and being capable of variation to adapt the invention to different types of doors, without departing from the spirit and scope of the invention.

Having described the invention what I claim as new and desire to have protected by Letters Patent is:—

1. An elevator door embodying therein the combination with an overbalanced, downwardly movable, sliding door section, having a laterally projecting hanger bar thereon, and side rails secured adjacent the door opening carrying guides coöperating with said door, of a combined stop and latch member comprising a lock plate permanently secured to a side rail, a fitting having a stop thereon, a latch member carried by said fitting, said stop and said latch member being adapted to receive said hanger bar between them when the door is opened, and said fitting and said lock plate being provided with coöperating means whereby said stop member and said latch member may be simultaneously adjusted without varying the distance between them, and means securing said fitting and said lock plate in any adjusted position, and means carried by an elevator car coöperating with said latch member whereby the release of the hanger bar is prevented while a car is at the door opening.

2. An elevator door embodying therein the combination with an overbalanced, downwardly movable, sliding door section having a laterally projecting hanger bar thereon, and side rails secured adjacent the door opening carrying guides coöperating with

said door, of a combined stop and latch member comprising a lock plate having a sequence of teeth thereon extending beyond said side rail and presented toward the door
 5 section, permanently secured to a side rail, a fitting comprising a base, a side flange adapted to engage one side of said lock plate, an overhang projecting across said lock plate and a toothed plate having a stop at
 10 the top thereof and teeth thereon adapted to coöperate with the teeth upon said plate, a latch member mounted upon the base of said fitting, said stop being adapted to engage the bottom, and said latch member being adapted to engage the top of said hanger bar when the door is opened, and means whereby the coöoperating teeth upon said lock plate and said other plate may be held in the operative position, and means
 15 20 carried by an elevator car coöoperating with said latch member whereby the release of the hanger bar is prevented while a car is at the door opening.

3. An elevator door embodying therein the combination with an overbalanced, downwardly movable, sliding door section having a laterally projecting hanger bar thereon, and side rails secured adjacent the door opening carrying guides coöoperating with
 25 30 said door, of a combined stop and latch member comprising a lock plate having a sequence of teeth thereon extending beyond said side rail, and presented toward the door section, permanently secured to a side rail, a fitting comprising a base, a side flange adapted to engage one side of said lock plate, an overhang projecting across said lock plate and a toothed plate separable from said overhang, said plate and said
 35 40 overhang being connected by interlocking members, and said plate having a stop at the top thereof and teeth thereon adapted to coöperate with the teeth upon said lock plate, a latch member mounted upon the base of said fitting, said stop being adapted to engage the bottom, and said latch member being adapted to engage the top, of said hanger bar when the door is opened, and means whereby the coöoperating teeth upon
 45 50 55 said lock plate and said other plate may be held in the operative position, and means carried by an elevator car coöoperating with said latch member whereby the release of the hanger bar is prevented while a car is at the door opening.

4. An elevator door embodying therein the combination with an overbalanced, downwardly movable, sliding door section having a laterally projecting hanger bar thereon, and side rails secured adjacent the door opening carrying guides coöoperating with said door, of a combined stop and latch member comprising, a lock plate having a sequence of teeth thereon extending beyond said side rail and presented toward the door
 60 65 70 75 80 85 90 95 100 105 110 115 120 125 130

section, permanently secured to a side rail, a fitting comprising a base, a side flange adapted to engage one side of said lock plate, an overhang projecting across said lock plate and a toothed plate having a stop at the top thereof and teeth thereon adapted to coöperate with the teeth upon the said lock plate, a latch member mounted upon the base of said fitting, said stop being adapted to engage the bottom, and said latch member being adapted to engage the top, of said hanger bar when the door is opened, said lock plate having a vertically extending slot therethrough, and bolts passing through said slot and engaging said fitting, whereby the coöoperating teeth upon said lock plate and said other plate may be held in the operative position, and means carried by an elevator car coöoperating with said latch member whereby the release of the hanger bar is prevented while a car is at the door opening.

5. An elevator door embodying therein the combination with an overbalanced, downwardly movable, sliding door section having a laterally projecting hanger bar thereon, and side rails secured adjacent the door opening carrying guides coöoperating with said door, of a combined stop and latch member comprising a lock plate having a sequence of teeth thereon extending beyond said side rail, and presented toward the door section, permanently secured to a side rail, a fitting comprising a base, a side flange adapted to engage one side of said lock plate, an overhang projecting across said lock plate and a toothed plate separable from said overhang, interlocking members upon said plate and said overhang, said plate having a stop at the top thereof and teeth thereon adapted to coöperate with the teeth upon said lock plate, a latch member mounted upon the base of said fitting, said stop being adapted to engage the bottom, and said latch member being adapted to engage the top, of said hanger bar when the door is opened, said lock plate having a vertically extending slot, and said toothed plate and said side flange having openings therethrough and bolts passing through said slot and said openings respectively and engaging said toothed plate and said side flange, whereby the coöoperating teeth upon said lock plate and said other plate may be held in the operative position, and means carried by an elevator car coöoperating with said latch member whereby the release of the hanger bar is prevented while a car is at the door opening.

6. An elevator door embodying therein the combination with an overbalanced, downwardly movable, sliding door section having a laterally projecting hanger bar thereon, and side rails secured adjacent the door opening carrying guides coöoperating with said door, of a combined stop and latch member comprising, a lock plate having a sequence of teeth thereon extending beyond said side rail and presented toward the door

with said door, of a combined stop and latch member comprising a lock plate having a sequence of teeth thereon extending beyond said side rail and presented toward the door section, permanently secured to a side rail, a fitting comprising a base, a plurality of lugs spaced apart on said base and each having an opening therein, a side flange adapted to engage one side of said lock plate having openings therein registering with the openings in said lugs respectively, an overhang projecting across said lock plate and a toothed plate having a stop at the top thereof and teeth thereon adapted to coöperate with the teeth upon said lock plate, a latch member, means whereby said latch member may be pivotally mounted between said side flange and either of said

lugs, upon the base of said fitting, said stop being adapted to engage the bottom, 20 and said latch member being adapted to engage the top, of said hanger bar when the door is opened, and means whereby the co-operating teeth upon said lock plate and said other plate may be held in the operative 25 position, and means carried by an elevator car coöperating with said latch member whereby the release of the hanger bar is prevented while a car is at the door opening.

In witness whereof, I hereunto affix my 30 signature, in the presence of two subscribing witnesses, this 26th day of November 1917.

BENJAMIN WEXLER.
